BY

Poplham & Webster ATTORNEYS.

UNITED STATES PATENT OFFICE.

JOHN PRIMM PADGETT, OF CORBIN, KENTUCKY.

COUPLING DEVICE.

1,012,425.

Specification of Letters Patent. Patented Dec. 19, 1911.

Application filed November 21, 1910. Serial No. 593,469.

To all whom it may concern:

Be it known that I, JOHN PRIMM PADGETT, a citizen of the United States, and a resident of Corbin, in the county of Whitley and State of Kentucky, have invented a new and useful Coupling Device, of which the following is a full, clear, and exact description.

This invention relates to improvements in emergency draft appliances; and the object of the invention is to provide a chain which will more easily and more securely attach a draw-bar of one car to another car.

The invention consists of novel features and parts and combinations of the same, which will be more fully described herein-after and then pointed out in the claims.

A practical embodiment of the invention is represented in the accompanying drawings, in which—

Figure 1 represents a perspective of the abutting ends of two cars, in which the side of one car is broken away, showing my chain in position. Fig. 2 is an elevation of the chain in part perspective. Fig. 3 is a horizontal section through the chain and draw-bar, showing the chain in position.

My invention consists in substituting for one link of a coupling chain E the element C, which is provided with an opening, preferably lengthwise the chain, adapted to support closely the coupling pin B.

As shown in Fig. 3 the draw-bar A may be provided with a recess for admitting the element C and stopping it in exact position

to receive the coupling pin B. The chain is preferably provided with the usual hook D adapted either to penetrate a link or to hold a link laterally. To connect the draw-bar A to another car the chain E is thrown around the post F and hooked. With the element C constructed as it is, the chain can be used as an ordinary chain for any purpose without limitation, the pin of the draw-bar is more strongly supported and less liable to bend, break, or jar loose, and a doubled chain connection is provided between the pin and the other car very simply and effectively.

I do not limit myself to the exact form in which my invention is herein disclosed, any further than is indicated in the claims.

I claim:

1. A free chain coupling, comprising a series of flexibly connected elements; one of said elements being a hook; another being in the form of a sleeve provided with fin-shaped means having perforations adapted to receive the adjoining elements of the chain coupling.

2. A free chain coupling, comprising a series of flexibly connected elements; one of said elements being a hook; another being in the form of a sleeve provided with a fin perforated to receive the adjoining elements of the chain coupling.

JOHN PRIMM PADGETT.
